UNITED STATES PATENT OFFICE.

WILLIAM T. GRIFFITH, OF IRONDALE, OHIO.

STEEL VISE-TIE.

1,333,484.

Specification of Letters Patent.

Patented Mar. 9, 1920.

Application filed September 26, 1919. Serial No. 326,499.

To all whom it may concern:

Be it known that I, WILLIAM T. GRIFFITH, a citizen of the United States, residing at Irondale, in the county of Jefferson 5 and State of Ohio, have invented new and useful Improvements in Steel Vise-Ties, of which the following is a specification.

This invention relates to railroad ties and has for its object the provision of a tie embodying in its construction movable chair or rail supports which are adjusted toward or away from each other whereby to adjust the tracks or rails to the proper gage.

Another object is the provision of a tie of 15 this character in which the adjustable rail engaging members include blocks of wood upon which the rails rest directly, the function of these blocks being to provide elasticity and avoid the extreme solidity of an 20 all metal tie.

An important object is the provision of a device of this character which will be comparatively simple and inexpensive in manufacture, highly efficient in use, which may 25 be readily adjusted, which will remain in set position, and which will be a general improvement in the art.

With the above and other objects and advantages in view, the invention consists in 30 the details of construction to be herein-after more fully described and claimed, and illustrated in the accompanying drawings in which—

Figure 1 is a plan view of a railroad tie 35 constructed in accordance with my invention, the top cover being omitted.

Fig. 2 is a longitudinal sectional view therethrough, the covers being in place.

Fig. 3 is a central cross sectional view, 40 Fig. 4 is a cross sectional view on the line 4—4 of Fig. 1,

Fig. 5 is a cross sectional view on the line 5—5 of Fig. 1, looking at one end,

Fig. 6 is a detail bottom plan view of 45 the top cover in place, the body of the tie being in section.

Fig. 7 is a longitudinal sectional view through a modified form of tie showing the use of wooden rail supporting blocks.

50 Fig. 8 is a cross sectional view therethrough, taken through one of the blocks, and

Fig. 9 is a perspective view of one of the blocks.

55 Referring more particularly to the drawing, the numeral 10 designates the body of

the tie which is formed in trough-shape and preferably of steel. At each end, the tie is closed by a wall 11 having a rectangular recess 12 into which extends a hole 13. 60

Extending longitudinally along the center of the body 10 is a threaded rod 14 which is provided at its extremities with nuts disposed within the recesses 12. At one end the rod 14 is provided with an angular extension 16 extending through one of the holes 13 and adapted for engagement by a suitable socket wrench or the like, not shown, whereby the rod may be rotated. At certain adjusted positions, the other end of 70 the rod may be projected through the hole 13 in the other end wall. The rod 14 is provided with a longitudinally extending groove or keyway 17.

The rail supports comprise members 18 75 arranged in pairs and each is formed as a body extending transversely of the tie and having at its ends recesses, as shown at 19, for engagement upon inwardly extending flanges 20 formed at the top edge of the 80 tie. At the center of the tie the flanges are cut away, as shown at 21, to permit the initial engagement or insertion of the members 18. Each member 18 is provided on its top face with a longitudinal rib 22 and a lug 23 and the ribs and lugs on each pair of members coöperate to engage against the edges and the top of the base of a rail, respectively. Upon their undersides, the members 18 have formed thereon projections 90 24 which are provided with holes 25 which are formed smooth and through which the rod 14 passes. Threaded upon the rod 14 and engaging against the projections 24 are nuts 26 and associated with each nut is a 95 U-shaped locking member 27 having one arm engaging within the groove 17 and its other arm engaging against one side of the nut whereby to prevent casual rotation of the nuts. 100

In some instances I may find it desirable to close, at least partially, the top of the tie and in order to do this I provide a cover formed in three sections, the central one being designated by the numeral 28 and the 105 end ones, which are similar, by the numeral 29. Each section comprises a flat plate 30 which seats upon the upper edges of the tie body 10 and each section is held in place by a locking device comprising a pair of bolts 110 31, slidably through brackets 32 on the underside of the plate and pivotally connect-

ed at their inner ends by a member 33 from which extends a squared end 34 projecting upwardly through the plate. This head is engageable by a wrench so that it may be turned to move the bolts 31 into engagement beneath the flanges 20. The outer sections are spaced such a distance from the central section that the cover will not interfere with the adjustment of the rails.

10 In the use of the tie it will be seen that when the locking members 27 are removed the nuts 26 may be adjusted upon the rod 14 whereby to move the pairs of rail supporting members 18 with respect to each other so 15 that the distance between them and consequently the gage of the track, may be adjusted. Under certain conditions the rod 14 may be rotated by means of a wrench or the like, to effect proper adjustment.

20 Referring to Figs. 7, 8 and 9, it will be seen that I have modified my tie to avoid the solidity of an all metal tie. In these figures it will be seen that the construction is the same as in the preceding form except 25 that the rail supporting members 38 engage against opposite sides of a wooden block 39 which is of the proper size and shape to fit firmly within the tie in transverse relation thereto and which has at its ends grooves 30 40 for the accommodation of the flanges 20 at the upper edges of the tie. The provision of these grooves 40 provides flange portions 41 upon the blocks which engage upon the upper edges of the tie body. These members 38 carry overhanging rail base engaging members 42, as in the previous form. In fact, the only difference between this 35 structure and the previous form is the provision of the wooden blocks which move 40 with the rail engaging members 38, as the screw 14 is rotated.

While I have shown and described the preferred embodiment of my invention, it is of course to be understood that I reserve 45 the right to make such changes in the form, construction, and arrangement of parts as will not depart from the spirit of the invention or the scope of the subjoined claims.

Having thus described my invention, I 50 claim:—

1. A railroad tie comprising a trough-shaped hollow body having its end walls provided with rectangular recesses, a threaded bolt extending longitudinally within said body, inwardly extending flanges formed on the top edges of the sides of the tie body, rail supporting members arranged in pairs and each formed as a body extending transversely of the tie and having its

ends recessed for engagement upon said flanges, longitudinal ribs and overhanging lugs formed on the top surfaces of said members and engaging respectively against the edges and tops of the base of a rail, downwardly extending projections formed on 65 said rail supporting members and provided with holes for the passage of said rod, nuts threaded upon the ends of said rod and disposed within said recesses, and other nuts threaded upon said rod and engaging 70 against said projections.

2. A railroad tie comprising a trough-shaped hollow body having its end walls provided with rectangular recesses, a threaded bolt extending longitudinally within 75 said body, inwardly extending flanges formed on the top edges of the sides of the tie body, rail supporting members arranged in pairs and each formed as a body extending transversely of the tie and having its 80 ends recessed for engagement upon said flanges, longitudinal ribs and overhanging lugs formed on the top surfaces of said members and engaging respectively against the edges and tops of the base of a rail, downwardly extending projections formed on 85 said rail supporting members and provided with holes for the passage of said rod, nuts threaded upon the ends of said rod and disposed within said recesses, and other nuts 90 threaded upon said rod and engaging against said projections, and a removable cover formed in sections fitting upon the top of and forming a closure for the tie body. 95

3. A railroad tie comprising a trough-shaped hollow body having its end walls provided with openings, a threaded rod extending longitudinally of said body and extending through said openings, one end of 100 said rod being provided with an angular portion adapted for engagement by a wrench, nut members engaging said rod and held against rotation at the ends of said body, a pair of wooden blocks disposed within 105 said body and having flanges bearing upon the top edges of the sides thereof, said blocks being provided with holes for the passage of said rod, a pair of rail engaging members disposed upon said rod and engaging 110 opposite sides of each block, overhanging flanges formed on said members and engaging the bases of the rails, and nuts threaded upon said rod and engaging each of said members. 115

In testimony whereof I affix my signature.

WILLIAM T. GRIFFITH.
